PORTABLE COMPRESSOR

Filed Oct. 2, 1931

UNITED STATES PATENT OFFICE

WILLIAM PRELLWITZ, OF EASTON, PENNSYLVANIA, ASSIGNOR TO INGERSOLL-RAND COMPANY, OF JERSEY CITY, NEW JERSEY, A CORPORATION OF NEW JERSEY

PORTABLE COMPRESSOR

Application filed October 2, 1931. Serial No. 566,436.

This invention relates to compressor outfitts, but more particularly to a portable compressor outfit in which the compressor and the motor whereby it is driven are arranged 5 within the same housing.

One object of the invention is to prevent the heat radiating from the compressor and the motor from commingling with the intake air supply to the compressor.

10 Another object is to assure an uncontaminated intake air supply of the lowest possible temperature.

Other objects will be in part obvious and in part pointed out hereinafter.

15 In the accompanying drawing illustrating the invention and in which similar reference characters refer to similar parts,

Figure 1 is a side elevation partly broken away of a portable compressor outfit having 20 the invention applied thereto, and

Figure 2 is a transverse view through Figure 1 on the line 2—2 looking in the direction indicated by the arrows.

Referring more particularly to the drawing, A designates generally a portable compressor outfit and B a housing of which the roof C and an end wall D are indicated. The roof C serves as a protective covering for a compressor E which may be operatively 25 connected, in a well known manner, to an internal combustion engine F whereby it is driven. The internal combustion engine F is shown provided with the usual exhaust pipe G which may extend upwardly through 30 the roof C and into an exhaust deflector H mounted on the roof.

On the end of the compressor, as for instance exteriorly of the wall D, is a storage receiver tank J which is connected to 40 the compressor E by a suitable discharge pipe K through which the fluid compressed by the compressor may pass to the tank J. Superimposed upon the tank J, or upon a bracket L mounted above the tank J, is a second tank O to serve as a storage for the fuel 45 used for operating the engine F.

In accordance with the practice of the invention, means are provided to assure an uncontaminated air supply to the compressor 50 and at the prevailing atmospheric tempera-

ture, more specifically, to prevent the temperature of the intake air from being increased by the heat radiating from the engine F and the compressor. In furtherance of these ends the compressor E is provided 55 with an intake conduit or pipe P which extends upwardly to a point adjacent the roof C wherein is an opening or aperture Q for the admission of atmospheric air to the inlet opening or openings R of the pipe P. 60

Arranged around the opening Q is a frame S which supports a cover or roof T for the opening Q. The members comprising the frame S are suitably spaced with respect to each other to define openings U for the passage of the air to the inlet openings R. Secured to the frame S, in any well known manner to overlie the openings U, are screens V to strain foreign matter, such as dust, from the air flowing therethrough. Additional 65 means may, however, be provided to cleanse the air pumped by the compressor, as for instance, filters W which lie beneath the roof T and are secured to the intake pipe P for removing from the air such foreign matter as 70 may pass through the screens V.

Preferably a baffle X is disposed on the roof C between the exhaust deflector H and the opening U adjacent thereto to prevent the flow of exhaust gases to the intake openings 75 of the compressor.

The means provided for preventing the radiation of heat from the compressor and its prime mover to the inlet openings R comprises a shield device designated generally by 80 Y and consisting of a pair of plates Z and b which are slightly spaced with respect to each other to form therebetween an air gap or space c. The plates Z and b extend transversely of the housing to form a compartment d in the upper portion and in one end of the housing and thus isolate the filters W and the inlet openings R from the remainder 85 of the interior of the housing B.

The plates may be secured to the housing in 90 any convenient manner, as for instance by bolts e, which extend through flanges f and g of the plates Z and b respectively and through the side wall of the housing B. One 95 end of the plates Z and b may be seated 100

against the wall D and at the other end of the plate Z, which is the lowermost plate, is an upturned portion or flange *h*, the top surface *j* of which is shaped to conform to the inner surface of the roof C against which it seats.

In the plates Z and *b* are suitable apertures *k* to permit the pipe P to be inserted therein, and said apertures are normally sealed by 10 covers *o* which may be suitably secured to the plates Z and *b* and have apertures *p* therein to receive the body of the pipe P.

As an additional precaution intended to prevent heated air, such as that flowing from 15 the engine, from being drawn toward the openings U, baffles *q* are arranged on opposite sides of the roof C along which they extend. The baffles *q* may be suitably joined at one end to the baffle X and at their other 20 end to a baffle *r* at the end of the roof C. Suitable drain holes *s* may be formed in the baffles *q* and said baffles are conveniently secured to the housing B by the bolts *e*.

In practice the present invention has been 25 found to be highly efficient. This is due to the facts that only atmospheric air at the normal prevailing temperature is drawn into the compressor E and that the air is supplied to the intake openings R at a point where the 30 supply is least apt to become contaminated by dust and the like which may be placed in circulation in the air during the course of the work. This is particularly true when performing such work as tie-tamping where- 35 with compressors of this type are generally employed to supply the pressure fluid for motivating the tampers. As is well known the tamping material is usually of a dry nature so that a considerable amount of dust is released 40 from the mass by the tamper and agitated by the exhaust fluid issuing therefrom.

The present invention has been found to not only assure a clean air supply to the compressor but also to be highly effective as a 45 means for preventing the initial temperature of the atmospheric air from being increased by the exhaust gases issuing from the engine or by the heat radiating from the engine and the compressor.

50 I claim:

1. A portable compressor outfit comprising a housing, a compressor in the housing, a motor in the housing to drive the compressor, an air intake device for the compressor having an inlet opening above the compressor and the motor, and means for preventing the heat radiating from the compressor and the motor from mingling with the air flowing to the intake opening.

60 2. A portable compressor outfit comprising a housing having an aperture in the top thereof, a compressor in the housing, a motor in the housing to drive the compressor, an air intake device for the compressor having an 65 inlet opening adjacent the aperture to re-

ceive air therefrom, a roof overlying the aperture, and a shield cooperating with the housing to prevent the flow of heat from the motor and the compressor to the inlet opening.

70 In testimony whereof I have signed this specification.

WILLIAM PRELLWITZ.
